No. 735,073.

PATENTED AUG. 4, 1903.

W. L. DUNHAM & F. H. HOUGH.

VAPOR BURNER.

APPLICATION FILED OCT. 4, 1902.

NO MODEL.

UNITED STATES PATENT OFFICE.

WILLIAM L. DUNHAM AND FRANKLIN H. HOUGH, OF WASHINGTON,
DISTRICT OF COLUMBIA.

VAPOR-BURNER.

SPECIFICATION forming part of Letters Patent No. 735,073, dated August 4, 1903.

Application filed October 4, 1902. Serial No. 125,904. (No model.)

To all whom it may concern:

Be it known that we, WILLIAM L. DUNHAM and FRANKLIN H. HOUGH, citizens of the United States, residing at Washington, District of Columbia, have invented certain new and useful Improvements in Vapor-Burners; and we do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 This invention relates to certain new and useful improvements in vapor-burners; and it has for its object the provision of an inexpensive, durable, and efficient burner designed for heating purposes, in the use of 20 which either crude or refined petroleum or other oils which are adapted, when subjected to heat, to generate gas may be used, the burner being equally adapted for use when supplied with oil or with an admixture of oil 25 and steam or water, as may be preferred.

An essential object of the invention resides 30 in the peculiarity of construction, whereby the burner may be readily and quickly lighted without the necessity of applying heat there- 35 to for a great length of time, as is necessary with most burners of this character in which it is required that the entire burner should be thoroughly heated in order to generate gas before the same can be ignited.

35 Other objects and advantages of the invention will hereinafter appear.

To these ends and to such others as the invention may pertain the same consists in the novel construction of the burner and in the 40 peculiar arrangement, combination, and adaptation of parts, all as will be hereinafter more fully described, shown in the accompanying drawings, and then specifically defined in the appended claims.

45 The invention is clearly illustrated in the accompanying drawings, in which—

Figure 1 is a side elevation of a heating-stove equipped with our improved burner, a portion of the stove being broken away in 50 order to more clearly illustrate the application of the invention. Fig. 2 is a central

vertical section through the burner and its connections. Fig. 3 is a sectional detail taken horizontally through the body of the burner. Fig. 4 is a side elevation of the inner face of 55 one of the shell-sections, showing the spiral groove formed therein. Fig. 5 is an enlarged detail view in section vertically through a portion of the inner and the outer shell and coil seated in the grooved wall of the outer 60 shell.

Reference now being had to the details of the drawings by letter, A represents the body portion of the burner, which in general form is cylindrical and consists of two vertical halves or sections each having cast integral therewith vertically-disposed flanges B, through openings b in which bolts are passed in securing the sections together, as shown in Fig. 1 of the drawings. The vertical walls 7c of the burner are thin, and the inner wall is spirally grooved to receive the oil-supply pipe, which is wound spirally around the inner wall of the burner within said spiral groove, and the oil-pipe thus wound within 75 the inner wall of the burner is protected from the direct heat by means of a thin wall or casing of sheet metal C. By the provision of the grooving of the wall as described, the tubing when inserted in place will be partially 80 surrounded by the walls of the groove between the casing, the heat which is retained in the wall of the outer shell to radiate heat over a large amount of the surface of the coil-pipe, and owing to the thickness of 85 the outer shell the heat will be retained by the metal and serve to thoroughly vaporize the oil in the coil, and at the same time the coil is shielded from direct contact with the flame. 90

D is a metallic plate which forms the upper face of the burner, said plate being securely bolted to the upper face of the casing, as shown in Fig. 2 of the drawings. An arm or extension D' of said plate D is bent downward and attached to the outer edge of a concaved disk E, which disk serves as a seat for the flame when the burner is in use, as will presently appear. 95

F is a standard, the screw-threaded lower 100 end of which has engagement with an opening in the metallic plate D, the said screw-

threaded lower end entering the inner chamber of the burner at a central point, as shown. The standard F is provided with a central chamber F', having at its lower end an opening into the interior of the burner, said opening being controlled by a needle-valve G, the upper end of which is provided with a rack-bar G', with the teeth of which a pinion carried upon the inner end of a rod H engage. 5 The extreme outer end of the said rod H, which is extended through an opening formed in the side of the stove, is provided with a suitable handle or button H², by means of which it is rotated when it is designed to raise or lower 10 the needle-valve, as will be readily understood.

J is the oil-supply pipe, which enters the interior chamber of the burner at its upper end and is wound spirally around the inner 15 wall of the burner within the spirally-formed groove therein, and after thus winding spirally from the top to the lower edge of the burner the said pipe extends upward through the plate D at the upper end of the burner and 20 at its extreme upper end communicates, by means of the passage K, with the chamber L. After the oil-supply pipe has been thus seated within the spiral grooves formed in the inner wall of the burner the metallic shell or plate 25 C is inserted, thus forming to the spirally-grooved coil-pipe a protection from the direct rays of heat.

The burner is suspended over the concaved disk E in such a manner as to allow a slight 30 intervening space between the lower end of the burner and the concaved inner face of the disk, as shown in Fig. 1 of the drawings.

The oil-supply pipe J is designed to lead 35 from any suitable oil-receptacle in which oil is confined under pressure—as, for instance, the oil-tank M, which tank is provided with a supply-valve N, through which air may be forced by means of a suitable air-pump.

From the foregoing description of the invention 40 its operation and advantages will be readily understood. When it is designed to light the burner, it is simply necessary to apply heat to the burner by means of a torch or otherwise. The thin shell or partition C, 45 which separates the inner chamber of the burner from the spirally-coiled oil-supply pipe, will serve to permit the heat from the torch or other igniting device to be ignited at once to the spirally-coiled pipe, and the gas 50 will be thus generated without the necessity of heating the entire casting forming the burner. This spiral arrangement of the pipe within the burner presents a very large heating-surface of pipe to the heat and greatly expedites 55 the lighting of the burner. When the heat is thus applied to the burner for a sufficient time to generate gas and the gas thus generated has entered the chamber L, it is simply necessary to turn the button or handle J, thus 60 raising the needle-valve from its seat the required distance and permitting the gas to

enter the interior of the burner, where it is ignited at the lower edge of the burner, and the heat and flame coming into contact with the concaved inner face of the disk E are deflected 70 upward and outward against the inner walls of the stove. It will be seen at once that by the arrangement described a perfect control of the gas-supply to the burner is at all times assured.

While we have shown the burner as substantially cylindrical in cross-section, it is at once evident that this particular form is not necessary and that the burner may be made rectangular or of other forms, if desired, the essential feature residing in the spiral arrangement of the oil-supply pipe within the inner chamber of the burner and in the protecting 80 of the pipe by means of a thin protecting shell or plate, as described.

Having thus fully described our invention, what we claim as new, and desire to secure by Letters Patent, is—

1. A vapor-burner comprising an outer shell of metal, the inner concave face of which is 90 spirally grooved, a vaporizing-coil positioned in said groove, an inner shell retaining said coil in place in the groove, and a metal valve regulating a duct which communicates between the coil and the interior of the shell, as 95 set forth.

2. A vapor-burner, comprising two shells, the outer of which is made up of the two complementary sections having their inner concave faces spirally grooved, a vaporizing-coil 100 seated in said groove, an inner shell retaining said coil in place, and a valve regulating a duct which communicates between the coil and the interior of said inner shell, as set forth.

3. A vapor-burner, comprising an outer 105 conical-shaped shell having a wall of varying thickness, the inner concave face of which is spirally grooved, a vaporizing-coil seated in said groove, an inner cylindrical shell retaining the coil in said groove for regulating a 110 duct which communicates between said coil and the interior of the inner shell, as set forth.

4. A vapor-burner, comprising an outer 115 conical-shaped shell, made up of two complementary sections having their concave faces spirally grooved, a vaporizing-coil seated in 120 said grooves, an inner cylindrical shell retaining said coil in place, and a valve regulating a duct which communicates between said coil and the interior of the inner shell, as set forth.

5. A vapor-burner, comprising an outer 125 conical shell made up of two complementary flanged sections, the inner concave faces of the sections being spirally grooved, a vaporizing-coil seated in the grooves of said shells, an inner cylindrical shell retaining said coil in place and having its lower end flaring and in contact with the lower tapering ends of the outer shell-sections, as set forth.

6. A vapor-burner, comprising in combination with an outer conical-shaped shell, the in-

ner concave wall of which is spirally grooved, a vaporizing-coil seated in said groove, an inner cylindrical shell retaining said coil in place, a valve regulating a duct which communicates between said coil and the interior of the inner shell, and a deflecting-disk positioned underneath the shells, as set forth.

In testimony whereof we hereunto affix our signatures in presence of two witnesses.

WILLIAM L. DUNHAM.

FRANKLIN H. HOUGH.
